UNITED STATES PATENT OFFICE

2,557,838

FIRE EXTINGUISHER NOZZLE

Albert Brown Phister, Fort Thomas, Ky., assignor
to The Phister Mfg. Co., Cincinnati, Ohio, a
corporation of Delaware

Application November 28, 1947, Serial No. 788,510

1 Claim. (Cl. 299—129)

1

My invention relates to fire extinguisher nozzles and particularly to the nozzle adapted to be retained on the flexible tube through which the fluid is directed toward the source of the fire.

As typical of a type of fire extinguisher with which my new nozzle is adapted to be used, reference is hereby made to my Patent No. 1,794,982 of March 3, 1931. In an extinguisher of this type there is a receptacle for a supply of liquid and a chamber for retaining a charge of compressed gas. A single actuator operates both the valve from the compressed gas chamber to the liquid receptacle, and from the liquid receptacle to the discharge hose through which the extinguishing fluid is directed toward the fire. On the end of the discharge hose there is a spray nozzle which may be manually controlled to regulate the volume and subdivision of the liquid into a spray or a substantially solid stream according to the particular requirements.

Ordinarily the person using the extinguisher supports it with the left hand and manipulates the spray nozzle, after opening the control valve on the extinguisher, with his right hand. It has been found in nozzles heretofore in use that the facility of operating the nozzle, which usually has a thumb actuated lever, is often impaired by the hose causing the nozzle to be presented upside down or crosswise, so that actuation is extremely awkward and difficult.

It is toward the provision of a nozzle which may be turned without effort so that its thumb actuated lever will fall in a convenient position for easy control that my invention is directed. This not only greatly facilitates use of the extinguisher but increases the safety factor of the use of the extinguisher precisely at that time when its proper use will do most toward control of the fire.

The foregoing objects and other objects to which reference will be made in the following description and in the drawings, I accomplish by that certain arrangement and combination of parts of which I have shown a preferred modification.

In the drawings:

Figure 1 is a sectional view lengthwise of the nozzle.

Figure 2 is a sectional view along the lines 2—2 in Figure 1.

Figure 3 is a detail fragmentary view showing a modified type of coupling.

In the drawings on the flexible tube 1, the tapered corrugated sleeve 2 is retained by means of a clamp ring 3. The tapered sleeve has a

2

flange 4 which may be circumferentially flattened to be received within the jaws of a wrench. A collar 5 preferably formed integrally with the sleeve 2 has a cylindrical end forming a bearing 6 which is internally threaded as indicated at 7.

A yoke member 8 has a round annular base 9 which has an internal bore which permits it to be fully rotatable on the cylindrical end 6. A threaded nozzle plug 10 has an orifice 11 extending therethrough. Surrounding the orifice the walls of the plug form a valve seat. The plug has a reduced inner end 12 threaded as indicated at 13 for engaging the internal threads 7 of the cylindrical end 6 of the sleeve.

15 The yoke 8 has a post 14 secured between the arms of the yoke and a trunnion 15 which journals the turned down flanges 16 of the thumb actuating lever 17. The lever has a thumb engagement portion 18 and an extension 19 to which 20 is secured a conical member 20. The apex of the cone forms a valve which engages the seat formed by the wall surrounding the orifice 11 of the plug and thus forms a spray controlling valve. The elements 8, 9, 14, 15, 17, 18, 19, mounted on the 25 trunnion or axle 15, provides the thumb lever actuator assembly and as noted it is freely rotatable about the axis of the tube.

By pressing down on the portion 18, the apex of the conical member is moved out of engagement with the seat surrounding the orifice 11. With 30 the initial movement the stream first is directed against the wall of the cone so as to spread out and form a spray in a wide arc. Further depression of the thumb piece 18 results in clearing the cone 20 from the path of the spray which is 35 then projected in the form of a stream.

The particular feature of the construction which facilitates movement of the control for the nozzle to a position of convenient control is the 40 yoke construction with its annular external bearing element 9, which rotates freely on the cylinder bearing 6. The base portion 9 is restrained from lengthwise movement by its end edges which fit between the collar 5 and the flange 21 of the plug which also is preferably conveniently circumferentially flattened for engagement by a wrench.

The modification shown in Figure 3 is the same as that shown in Figures 1 and 2, excepting that 50 instead of the sleeve having a tapered corrugated tip, it is provided with a threaded end 22 which engages within the threads of a coupling member 23 held in position on the hose with a ring clamp 24.

To keep the thumb lever with the spray con-

trol valve in closed position, a spring member 25 having an end 26 extends along underneath the thumb piece. The spring illustrated makes several turns about the trunnion member 15 and has its inner end 27 blocked by contact with the post 14.

Modifications in the specific details of structure will readily occur to those skilled in the art. While this construction of spray nozzle is particularly adapted for fire extinguishers it will, with slight modification, serve a useful purpose on garden spray apparatus and the like.

In the use of the device it has been found that without a deflector plate, such as is indicated at 28, the spray at the initial start of opening the valve will run up on the inside of the lever 17 and cover the person using the device with spray. Accordingly, the deflector plate to prevent this has been found desirable.

Having thus described my invention, what I claim as new and desire to secure by Letters Patent is:

A spray nozzle provided with means for attachment to a flexible tube through which liquid is projected under pressure and comprising a nozzle tip assembly having a valve seat member provided with a discharge orifice extending medially therethrough, said nozzle tip assembly having an external cylindrical bearing surface, a cone shaped valve of such size and shape as to act as a deflector when moved from said valve seat, a pivoted thumb lever on which said valve is mounted having spring tensioned means to urge said valve against the seat, an annular base member having an internal bearing surface adapted just nicely to engage said external cylindrical bearing

5
10

surface for rotation about the axis of said discharge orifice, said base member being fixed against axial movement with respect to said nozzle tip assembly, and means for pivotally mounting said thumb lever on said annular base, said last mentioned means comprising a pair of extensions fixed to said annular base member, a trunnion mounted on said extensions, a pair of flanges fixed to said lever and journaled on said trunnion, a pin mounted between said extensions, and a torsional spring surrounding said trunnion, one end of said spring engaging said lever and the other end of said spring engaging said pin.
